(57) **CLAIM**

The ornamental design for a greenhouse container, as shown and described.

DESCRIPTION

FIG. 1 is a perspective view of a greenhouse container showing our new design in closed position.

FIG. 2 is a front elevational view thereof.

FIG. 3 is a right side elevational view thereof.

FIG. 4 is a rear elevational view thereof.

FIG. 5 is a left side elevational view thereof.

FIG. 6 is a top plan view thereof.

FIG. 7 is a bottom plan view thereof.

FIG. 8 is a perspective view of a greenhouse container in an open position.

FIG. 9 is a front elevational view thereof.

FIG. 10 is a right side elevational view thereof.

FIG. 11 is a rear elevational view thereof.

FIG. 12 is a left side elevational view thereof.

FIG. 13 is a top plan view thereof; and,

FIG. 14 is a bottom view thereof.
